UNITED STATES PATENT OFFICE.

ALVIN D. KEENE, OF PITTSBURGH, PENNSYLVANIA, ASSIGNOR TO WESTINGHOUSE ELECTRIC & MANUFACTURING COMPANY, A CORPORATION OF PENNSYLVANIA.

FURNACE RESISTOR MOUNTING.

Application filed November 20, 1923. Serial No. 675,864.

To all whom it may concern.

Be it known that I, ALVIN D. KEENE, a citizen of the United States, and a resident of Pittsburgh, in the county of Allegheny and State of Pennsylvania, have invented a new and useful Improvement in Furnace Resistor Mountings, of which the following is a specification.

My invention relates to furnaces and particularly to electrically-heated resistance furnaces.

One object of my invention is to provide a relatively simple resistor mounting for electrically heated resistance furnaces.

15 A further object of my invention is to provide a relatively simple means for mounting a resistor as a unit.

In practicing my invention, I provide a plurality of refractory heat-insulating walls 20 enclosing a furnace chamber and supporting a plurality of spaced sets of refractory members, of substantially T-shape, projecting into the furnace chamber. The refractory members of T-shape are spaced apart laterally, and relatively thin, narrow, perforated, refractory plates are held by the outer ends of the members of T-shape. A relatively heavy resistor member, preformed to comprise a plurality of straight and substantially 30 parallel-extending return bent convolutions, is held by the perforated plates whereby the convolutions extend substantially parallel to the furnace walls and closely adjacent thereto.

35 In the single sheet of drawings,

Figure 1 is a view in vertical section, of an electrically heated furnace embodying my invention;

Fig. 2 is a fragmentary view, partly in 40 side elevation and partly in longitudinal section, of an electrical resistance furnace embodying my invention;

Fig. 3 is a fragmentary view, in front elevation, of a refractory member, a resistor, and refractory supporting members;

Fig. 4 is a fragmentary view, partly in 45 longitudinal section and partly in side elevation, of an electrical resistance furnace showing a further embodiment of my invention; and

Fig. 5 is a view, in front elevation, of a 50 plurality of refractory members, and resistors as shown in that embodiment of my invention in Figure 4.

55 An electric furnace designated generally

by the numeral 6 comprises an outer casing 7 of suitable heat-insulating refractory material constituting the walls of the furnace chamber. An inner lining 8 is located within the casing 7 and comprises suitable 60 high-temperature resisting refractory material such as is usually employed in the art. The walls are suitably spaced apart to constitute or enclose a furnace chamber 9 of any suitable or desired contour and dimensions. 65

Refractory supporting members 10, of substantially T-shape ends extend into the furnace chamber. The members 10, of substantially T-shape, are more particularly illustrated in Figures 2, 3 and 4 of the 70 drawing and, as are shown, are provided with two depressions 11 and 12 of unequal depths, located in opposing surfaces of, and adjacent, the end of the T-shaped member. As hereinbefore stated, the members 10 are 75 located in spaced relation and relatively thin and narrow refractory members or bars 15 each having a plurality of perforations extending laterally through the plate between opposite surfaces, are supported by cooperating members 10 immediately adjacent the wall of the furnace.

In another embodiment, as shown in Figure 3, the depressions 11 and 12 have substituted therefor the laterally extending 85 grooves 13 and 14.

Means for preventing lateral movement of the members 15 relatively to the supporting members 10 may comprise metal rods 16, of substantially L-shape, which are dropped 90 into spaced openings 17, the width of the member 15 being such as to extend substantially between the two members 16 to be held thereby against lateral movement relatively to the supporting member 10. 95

A resistor member 18 is located between adjacent perforations 19 and extends between and beyond these resistor-supporting members and comprises a plurality of straight and substantially parallel-extending 100 return-bent convolutions of a relatively heavy resistor bar or rod which is self supporting between and beyond the resistor supporting members 15.

The resistor member is held against the bars 15 by means of metal members 20, of substantially hair-pin shape, that extend through the hereinbefore mentioned perforations, the ends of the members 20 being bent over against one surface of the bar 15. 105 110

Fig. 4 illustrates another method of mounting the resistor element upon the resistor supporting members and shows the use of more than one resistor element secured to the resistor-supporting members in such a manner that maximum radiating surfaces of both resistors is secured.

A second preformed resistor is located against the other surface of the bars 15 by clamps 20, the convolutions at the front and at the back being staggered relatively to each other.

While I have illustrated the heating elements as located in the end and side walls only, the same general construction may be employed in the roof of a furnace.

In assembling the parts embodying the furnace structure the supporting members of T-shape are located in proper spaced relation, substantially as illustrated in the drawing, and in mounting the heating element, which has previously been secured to the resistor supporting members by clamps of substantially hair-pin shape 20, the individual members 15 may be slipped into place back of the overhanging flanges by a tilting and lateral and downwardly directed movement of the entire unit. If the structure such as illustrated in Fig. 3 is used, the unit is slipped into place behind the overhanging flanges of the member of T-shape adjacent the walls and the locking keys 21 and 22 may then be placed in position, thus, completing the installation of the resistor member.

Various modifications may be made in the device embodying my invention and I desire that only such limitations shall be placed thereon as are imposed by the prior art or are specifically set forth in the appended claims.

I claim as my invention:

1. In an electric resistance furnace, in combination, a refractory wall, a plurality of refractory members, of substantially T-shape, supported by said wall, a resistor-supporting member extending between said refractory members and a plurality of resistor members secured to said resistor-supporting members on opposite sides thereof.

2. In an electric resistance furnace, in combination, a refractory wall, a plurality of refractory members, of substantially T-shape, projecting from said wall, a resistor-supporting member extending between said refractory members, and a plurality of resistor members secured to said resistor-supporting member.

3. In an electric resistance furnace, in combination, a plurality of refractory walls enclosing a furnace chamber, a plurality of refractory members, of substantially T-shape, supported by said wall, a plurality of relatively narrow resistor-supporting members, extending between said refractory

members, and a resistor member secured to the resistor-supporting members whereby the resistor-supporting members and resistor member may be unitarily placed in an operative position.

4. In an electric furnace, in combination, a plurality of refractory walls enclosing a furnace chamber, a plurality of refractory members supported by one of said walls in said chamber, a plurality of resistor-supporting members extending between said refractory members and a plurality of alternately spaced resistor members secured to different surfaces of said refractory members.

5. In an electric resistance furnace, in combination, a refractory wall, a plurality of spaced sets of refractory members, of substantially T-shape, having laterally grooved opposite surfaces supported by said wall, resistor-supporting members extending between spaced pairs of said refractory members, and a plurality of resistor members secured to said resistor-supporting members.

6. In an electric resistor furnace, in combination, a plurality of refractory walls enclosing a furnace chamber, a plurality of refractory members supported by one of said walls and projecting into said chamber, a perforated resistor-supporting member extending between said refractory members, a resistor member and means associated with said perforations in said refractory member whereby said resistor member is secured to said resistor-supporting member.

7. In an electric resistance furnace, in combination, a plurality of refractory walls enclosing a furnace chamber, a plurality of refractory members supported by one of said walls and projecting into said chamber, a perforated resistor-supporting member extending between said refractory members, a resistor member, and a relatively narrow resistor securing means associated with the perforations in said refractory member whereby a maximum resistor radiating surface is maintained.

8. In an electric resistance furnace, in combination, a refractory wall, a plurality of spaced sets of aligned and spaced refractory members, of substantially T-shape, supported by said wall, each member having depressions in opposite surfaces, and resistor-supporting members extending between opposed pairs of said refractory members, having their ends operatively located respectively in said depressions by a tilting and lateral and downwardly directed movement, and a plurality of resistor members secured to the opposite surfaces of the resistor supporting members.

9. In an electric resistance furnace comprising a plurality of refractory walls enclosing a furnace chamber, a heater element

comprising a plurality of resistors, a plurality of refractory resistor supports and means for securing said resistors to said supports in alternately spaced positions.

10. In an electric resistance furnace comprising a plurality of refractory walls enclosing a furnace chamber, a heater element comprising a plurality of resistors, a plurality of perforated refractory resistance

supports and a relatively narrow means associated with the perforations in said supports for securing said resistors to said supports whereby a maximum resistor radiating surface is maintained.

In testimony whereof, I have hereunto 15
subscribed my name this 14th day of No-
vember 1923.

ALVIN D. KEENE.
